UNITED STATES PATENT OFFICE.

JOHN WILLIAM SIMMONDS, OF ATTLEBOROUGH, MASSACHUSETTS, ASSIGNOR
TO THE J. M. FISHER & COMPANY, OF SAME PLACE.

BROOCH.

SPECIFICATION forming part of Letters Patent No. 645,302, dated March 13, 1900.

Application filed August 21, 1899. Serial No. 727,885. (No model.)

To all whom it may concern:

Be it known that I, JOHN WILLIAM SIMMONDS, of Attleborough, in the county of Bristol and State of Massachusetts, have invented a new and useful Improvement in Brooches; and I hereby declare that the following is a full, clear, and exact description of the same, reference being had to the accompanying drawings, forming part of this specification.

This invention has reference to an improvement in the class of brooches in which a glass disk or crystal is inserted and a miniature or ornament may be inserted.

15 The invention consists in the peculiar and novel construction whereby ready access may be had to the interior of the brooch and the brooch secured, as will be more fully set forth hereinafter.

20 Figure 1 is a front view of my improved brooch. Fig. 2 is a rear view of the same, and Fig. 3 is a vertical sectional view.

In the drawings, *a* indicates the rim, which is shown scalloped and beaded, but may be of any ornamental design; *a'*, the flange against which the crystal *b* bears; *b'*, a spring-ring for holding the crystal *b* in place; *c*, the cover, secured by the hinge *c'* to the upper part of the rim *a* and provided with the snap-latch *c*², by

25 which the lower part of the cover is secured. The edge of the cover *c* fits into the annular recess *a*² in the rim. To the cover is attached the pin *d*, pivotally secured in the hinge *d'* and fastened by the hook *d*². By this con-

struction the brooch is more readily secured 35 than it was when the pin was hinged to one side of the rim and the fastening-hook to the other side, in which construction the point of the pin projected beyond the rim and was liable to injure the wearer and catch loose 40 garments or ribbons.

My improved brooch can be readily opened while it is secured and miniatures or other articles inserted or removed without detaching the brooch.

Having thus described my invention, I claim as new and desire to secure by Letters Patent—

In a brooch, the combination with the circular rim *a*, the flange *a'*, the circular crystal 50 *b*, and the spring-ring *b'*, of the cover *c* the edge of which enters the annular recess in the rim, the annular recess *a*², the hinge *c'* securing one edge of the cover, the snap-latch *c*² on the cover arranged to snap over the edge 55 of the rim, and the pin *d* pivotally secured to the cover and engaged with the hook *d*² on the cover; whereby the fastening-pin is supported by the cover and covered by the brooch, as described.

In testimony whereof I have signed my name to this specification in the presence of two subscribing witnesses.

JOHN WILLIAM SIMMONDS.
